UNITED STATES PATENT OFFICE

118,432

DESIGN FOR A SAFETY HAT

Howard B. Lewis, Venice, Calif.

Application October 2, 1939, Serial No. 87,473

Term of patent 14 years

To all whom it may concern:

Be it known that I, Howard B. Lewis, a citizen of the United States, residing at Venice, in the county of Los Angeles and State of California, have invented a new, original, and ornamental Design for a Safety Hat, of which the following is specification, reference being had to the accompanying drawing, forming part thereof.

Fig. 1 is a plan view of the safety hat embodying my new design;

Fig. 2 is a side view; and

Fig. 3 is a front view thereof.

I claim:

The ornamental design for a safety hat, as shown.

HOWARD B. LEWIS.
